UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,266,023.

Specification of Letters Patent.

Patented May 14, 1918.

Application filed February 24, 1917. Serial No. 150,688.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States No. 436,532, to O. Mergenthaler, wherein circulating matrices are released from a magazine in the order in which their characters are to appear in print and then assembled in line, the composed line transferred to the face of a mold, the mold filled with molten metal to 15 form a slug or linotype against the matrices which produce the type characters thereon, and the matrices thereafter returned through distributing mechanism to the magazine from which they started. In these machines, the matrices when released from the magazine pass down or through a vertical channeled raceway or front plate and onto the upper stretch of an inclined endless conveyer belt from which they pass through a 20 guide throat or chute to an assembler, wherein they are composed in line under the influence of a rotary star wheel.

As ordinarily constructed, the throat is constituted at its lower side by "assembler rails" partly inclosing the star wheel, and at its upper side by a "chute spring" which is arranged to contact with the side faces of the matrices as they pass through the throat. Originally, the chute spring was attached 25 to a fixed part of the machine, with its lower end at a given distance from the assembler rails, such distance being chosen so as to provide for the proper guidance of the thinner matrices and to allow the spring to 30 yield in guiding the thicker matrices. In the use of this construction, it frequently happened that the matrices would become clogged or piled up in the throat for one reason or another, and particularly because 35 the spring unduly retarded the passage of the thicker matrices to which it necessarily offered greater resistance than to the thinner ones. The objection became quite pronounced upon the advent of the more modern machines, which are or may be equipped

with matrix fonts of widely varying sizes. To meet this new condition, it was proposed to mount the chute spring so that it could be adjusted (either manually or automatically) to different operative positions so as 60 to vary the width of the assembler throat to correspond to the different matrix fonts. While this adjustment of the chute spring materially reduced the liability to clogging, the objection was not entirely eliminated 65 owing to the fact that the matrices in an individual font themselves vary in thickness to a considerable extent. In addition, the necessity for adjustment required the special attention of the operator and involved the 70 addition of other parts which served to complicate the machine construction.

It is the object of my present invention to overcome the foregoing and other difficulties, and contemplates a construction wherein the 75 matrices, irrespective of size or font, may be accurately and positively guided to the assembler in the proper manner, without the use of any additional parts or without requiring any attention whatever on the part 80 of the operator. To this end, I propose to construct the assembler throat so that the matrices may be guided therethrough by their projecting ears, which as well known are of substantially uniform thickness throughout the font or fonts. Specifically, I substitute for the former chute spring a fixed 85 trough-shaped guide facing downward toward the assembler rails and having its side flanges arranged in position to engage the 90 projecting ears of the matrices as the latter pass to the assembler. In this way, all of the matrices, whether thick or thin, are guided in the same positive manner without being subject to any different retarding influences.

In the drawings:

Figure 1 is a front view of a portion of a linotype machine having my invention applied thereto;

Fig. 2 is an enlarged view of the assembling devices immediately concerned with my invention;

Fig. 3 is a detached perspective of the improved trough-shaped guide; and

Fig. 4 is a section on the line 4—4 of Fig. 2.

The machine illustrated is of the kind known to the trade as "Model 9," comprising four magazines A containing matrices X of 110

as many different fonts, which may differ in size to any desired extent, and any selected one of which may be brought into use by the operation of the hand lever A¹. The 5 matrices are released from the selected magazine by the manipulation of the keyboard B, whence they pass down or through the channelled raceway or front plate C onto the inclined endless conveyer belt D which is 10 continuously driven in the usual way. As the matrices leave the belt, they pass through a throat or chute E into the assembler F, wherein they are composed in line under the influence of the rotary star 15 wheel F¹.

The matrices X are of the regular construction, each being provided on its opposite edges with the customary projecting ears X¹, which, for the purpose of the present case, may be regarded as of the same thickness throughout a font or fonts. These 20 projecting ears are located at one side of the individual matrices (except of course the very thin ones which are of no greater thickness than the ears themselves) and that side during composition is the rear or following one. When, therefore, the matrices are 25 delivered to the conveyer belt, they lie upon their rear sides or with their forward sides 30 facing upward (see Fig. 2). The result is that, although the matrices may vary widely in relative thicknesses, their projecting ears being of substantially the same thickness 35 pursue the same path and are presented to the assembler throat in the same relation. This feature plays an important part in the use of my improvement, which will now be described.

As previously indicated, my invention 40 contemplates the construction of the assembler throat so that the matrices passing therethrough may be guided by their ears instead of by their side faces as heretofore. In the present instance, the bottom side of 45 the throat is constituted as before by the curved assembler rails E¹ partly inclosing the star wheel F¹ and leading from the discharge end of the belt to the entrance of the assembler F. In carrying out my invention, 50 however, I provide for the upper or opposite side of the throat a trough-shaped guide E² screwed or otherwise secured to the framework of the face plate C. As shown clearly 55 in Fig. 2, the guide E² faces downward toward the assembler rails and has its depending flanges formed and arranged to receive the body portions of the matrices between them and to engage only the projecting ears of the matrices as they pass through the 60 throat. The relative location of the guide flanges and the assembler rails is such that the throat or chute E constituted thereby, as shown, is flared at its receiving end and is most restricted at or about midway of the 65 assembler rails, the width of the throat at

its restricted portion corresponding approximately to the thickness of the matrix projecting ears. It will be apparent, therefore, that as the matrices leave the conveyer belt 70 their projecting ears will first strike the depending flanges of the guide E² and be deflected thereby downward toward the assembler, being held in close contact with the underlying rails E¹ until they assume a more nearly erect position, at which time 75 they are engaged by the star wheel F¹ and pushed or advanced sidewise into the assembler F. In this connection, it is pointed out that the bottom side of the trough-shaped guide E² is cut away, as at E³, so 80 as to permit the matrices to assume the position described, it also being noted that the lower ends of the depending flanges are curved or pointed to avoid binding against the ears of the matrices as the latter leave 85 the throat. Since their projecting ears are of substantially the same thickness throughout the font or fonts, it follows that my improved arrangement is capable of coöperating with matrices of all sizes or fonts and 90 delivering them to the assembler under positive and uniform control.

I have shown my invention merely in preferred form and by way of example, and as 95 applied to a linotype machine of the kind mentioned, and it is obvious that many modifications and alterations therein and in its mode of operation will readily suggest themselves to those skilled in the art without departure from its scope.

Having thus described my invention, its construction and mode of operation, what I claim and desire to secure by Letters Patent of the United States, is as follows:

1. In a typographical machine comprising 105 matrices formed with projecting ears at their opposite ends, the combination of a magazine to contain the matrices, an assembler wherein the matrices are composed in line, means for delivering the matrices to 110 the assembler in unreversed position, and guiding means to coöperate with the matrices in their passage to the assembler, the said guiding means including a flange to engage the projecting ears at both ends of 115 the matrices at one side and confine them to their proper path of travel.

2. Typographical assembling mechanism capable of handling matrices formed with 120 projecting ears at both ends and including, in combination, an assembler wherein the matrices are composed in line, a conveyer belt for delivering matrices to the assembler, and an intermediate throat whereby the matrices are conducted from the conveyer belt 125 to the assembler in unreversed position, the said throat having a flange to engage the projecting ears at both ends of the matrices at one side to guide them properly in their 130 passage through the throat to the assembler.

3. Typographical assembling mechanism capable of handling matrices formed on opposite edges with projecting ears and including, in combination, an assembler wherein the matrices are composed in line, a conveyer belt for delivering matrices to the assembler, and an intermediate throat whereby the matrices are conducted from the belt to the assembler in unreversed position, the 5 said throat having at one side a pair of guide flanges arranged in position to engage the projecting ears on the opposite edges of the matrices as the latter pass therethrough.
- 10 4. Typographical assembling mechanism capable of handling matrices formed with projecting ears and including, in combination, an assembler wherein the matrices are composed in line, a conveyer belt for delivering 15 matrices to the assembler, rails leading from the discharge end of the belt to the entrance of the assembler, and a trough-shaped guide overlying the rails, the said 20 guide facing downward toward the rails and having its flanges arranged in position to engage the projecting ears of the matrices 25 as they pass therealong.
5. Typographical assembling mechanism capable of handling matrices formed with 30 projecting ears and including, in combination, an assembler wherein the matrices are composed in line, a conveyer belt for delivering matrices to the assembler, rails leading from the discharge end of the belt 35 to the entrance of the assembler, and a trough-shaped guide overlying the rails and having its bottom side cut away at or near the lower end, for the purpose described.
6. Typographical assembling mechanism 40 capable of handling matrices formed with

projecting ears and including, in combination, an assembler wherein the matrices are composed in line, a conveyer belt for delivering matrices to the assembler, rails leading from the discharge end of the belt to the 45 entrance of the assembler, and a trough-shaped guide overlying the rails and having its flanges curved or pointed at their lower ends, for the purpose described.

7. Typographical assembling mechanism 50 capable of handling matrices formed with projecting ears and including, in combination, an assembler wherein the matrices are composed in line, a conveyer belt for delivering matrices to the assembler, intermediate rails constructed and arranged to receive the matrices from the discharge end of the belt and deliver them to the assembler in unreversed position, and a guide flange overlying the rails and arranged in position to 55 engage the projecting ears of the matrices 60 as they pass therealong.

8. Typographical assembling mechanism capable of handling matrices formed on opposite edges with projecting ears and including, in combination, an assembler wherein the matrices are composed in line, a conveyer belt for delivering matrices to the assembler, intermediate rails constructed and arranged to receive the matrices from the discharge 65 end of the belt and deliver them to the assembler in unreversed position, and a pair of guide flanges overlying the rails and arranged in position to engage the projecting ears of the matrices on their opposite edges 70 75 as they pass therealong.

In testimony whereof, I have affixed my signature.

DAVID S. KENNEDY.
